SEAL FOR A POTHHEAD HOODNUT

Robert A. Philibert, Rockville Centre, Frank L. Browne, Wantagh, and Robert F. Polimine, Brooklyn, N.Y., assignors to O.Z. Electrical Manufacturing Co., Inc., Brooklyn, N.Y., a corporation of New York

Filed Jan. 7, 1966, Ser. No. 519,330
 1 Claim. (Cl. 174—19)

This invention relates to potheads, and more particularly pertains to a seal for a removable hoodnut for the pothead.

It has been found that the use of potheads having removable hoodnuts have often developed leakage and that the insulation of the cables terminated in the pothead has become deteriorated.

An investigation into this matter discloses that the formation of air pockets during the insertion of the compound into the pothead leaves spaces which may cause trouble. In particular, since the pothead is filled with insulating compound while it is heated, the cooling of the compound causes it to contract and in effect create air pockets with a lower pressure than the ambient air pressure which has a tendency to suck in air from the outside and moisture along with it under certain conditions. Also, when a considerable amount of current is being carried by the conductor terminating in the pothead, the pothead becomes heated. This causes the air in the spaces not filled with compound to develop pressures tending to cause such air to find leaks for escaping. If the pothead hoodnut seal is not perfect, air will flow out of the pothead and upon the reduction of the current load, when the pothead cools, a vacuum will develop which will draw air with moisture into the pothead.

The moisture alone within the pothead will cause the cable insulation to lose its dielectric properties, particularly when paper insulated lead cable is employed. It is also known that corona discharges cause a formation of ozone, and ozone is known to cause the erosion of cable insulation. Also, corona develops at lower potential values when moisture is present. Thus, it is of utmost importance that air with moisture contained therein be excluded from the pothead. Basically, a pothead is a hermetic seal to keep air and moisture away from the internal stress cone termination for the cable.

The purpose of the present invention is to provide an improved seal between the hoodnut (or capnut) and the body portion of the pothead insulator.

It is the purpose of the present invention to not only increase the pressure which the seal will withstand without leakage, but also to so construct the seal that it will maintain its effectiveness over a period of time without deterioration.

Other objects, purposes and characteristic features of the present invention will be in part obvious from the accompanying drawings, and in part pointed out as the description of the invention progresses.

In describing the invention in detail, reference will be made to the accompanying drawing, in which like reference characters designate corresponding parts throughout the several views, in which—

FIG. 1 illustrates a vented hoodnut with the usual flat seal between the hoodnut and the insulator such as might be used in D'Ascoli et al. Patent No. 3,151,209, granted Sept. 29, 1964, without the hoodnut being tightened down;

FIG. 2 illustrates the hoodnut of FIG. 1 as being fully tightened and showing the deformation of the rubber seal;

FIG. 3 illustrates a hoodnut constructed in accordance with the present invention but not yet tightened down;

FIG. 4 illustrates the hoodnut of the present invention

fully tightened with the disposition of the seal being determined by the nature of the hoodnut embodying the present invention; and

FIG. 5 is a partial sectional view of a hoodnut to show the shape of the groove placed therein (enlarged) and shown in FIGS. 3 and 4.

In referring to FIG. 1 of the D'Ascoli et al. Patent No. 3,151,209, it will be noted that the space between the stem 26 and the insulator 14 is relatively small. It was thought that such a small spacing might prevent the adequate flow of the hot insulating compound even though the air might be vented through an appropriate vent. Therefore, the structure was modified to include adequate spacing for the compound to flow; a screw closed vent 29 was added to the hoodnut; and a flat gasket or washer 27 was inserted between the hoodnut 28 and the insulator 14, as shown in FIG. 1 of the drawings herein with hoodnut untightened. Such structure, with the hoodnut 28 tightened and the insulating compound inserted in the pothead in the usual way still had the same problems. Further investigation showed that the seal 27 spread or deformed unduly under the pressure of the tightened hoodnut 28 as shown in FIG. 2 herein. The seal 27 spread sufficiently to actually prevent the adequate venting of the air within the pothead during the insertion of the hot insulating compound.

Referring to FIG. 3, the insulator body portion 5 of the pothead of the present invention is so constructed internally near its upper end as to include winged portions 6 which cooperate with winged portions 7 on the stem 8 to prevent the turning of the stem 8 although allowing considerable free space for the passage of insulating compound into the air spaces above it. The particular formation of the insulator portion 5 is not limited to this particular form, but it should be provided with adequate structure for holding the stem 8 from turning and at the same time provide adequate passages for the flow of the insulating compound and venting of air from the threaded vent hole 9 during its construction.

The lower portion of the insulator body 5 has not been shown in the drawings, but it is assumed to be connected to a suitable metal bell (not shown) adapted to receive a cable through a suitable seal. It is also assumed that the metal bell has a threaded opening for a connection to a source of dielectric material or compound. This threaded opening also would have a threaded closing plug. This structure may be of any suitable type, and one such suitable form is shown, for example, in the above mentioned Patent No. 3,151,209. Also, the compound filling for the pothead can be any suitable dielectric material, or it can be the compound disclosed in such patent.

The capnut or hoodnut 10 is adapted to screw onto the threaded portion of the stem 8 after the flat sealing ring 11 is placed into position. This is shown in FIG. 3 where the hoodnut 10 has been just tightened sufficiently to contact the sealing ring 11.

It will be noted that the hoodnut or capnut 10 has a circular groove 12 included therein which has been illustrated in an enlarged sectional view in FIG. 5. In one embodiment of the invention this groove was in the order of $\frac{1}{8}$ -inch diameter with $\frac{1}{32}$ round corners. In this embodiment a sealing ring of "neoprene" rubber $\frac{1}{8}$ -inch thick was used. Neoprene was selected because it is basically a high Durometer rubber with low compressive set, wide temperature range and good tensile strength. It also resists erosion by ozone. Such sealing rings can be purchased from various suppliers; but any other suitable sealing ring of compressive material can also be used, if desired, such as nitrile (Buna N) artificial rubber.

Upon tightening the hoodnut 10 of this one embodiment of the invention to two hundred inch pounds torque, there was no blocking of the passageway by the sealing

ring 11 since it assumed the general shape shown in FIG. 4. There was no leakage from the gasketed vent screw 13 and there was no leakage around the seal 11 at one hundred twenty pounds per square inch internal air pressure.

In fact, tightening of the hoodnut 10 to seven hundred inch-pounds torque did not cause the sealing ring 11 to expand unduly, but it still allowed a free passageway for the venting air and for receiving the insulating compound. When the unit was disassembled, the sealing ring 11 was not scraped or cut in any way.

On the other hand, the tightening of the hoodnut 28 of FIG. 2 to approximately 700 inch-pounds torque caused slight cutting or abrasion of the sealing ring 27 besides causing it to protrude and block the vent hole 29 as shown in FIG. 2. In fact, the tightening of the hoodnut 28 of FIG. 2 to approximately 250 inch-pounds torque caused the sealing ring to expand and block the flow of air from the vent hole 29, although such pressure did not cut the sealing ring.

Before inserting the ring 11, it was suitably covered with a special lubricating grease compatible with rubber. The grooved portion 12 of the hoodnut 10 and the flat portion 15 of the insulator 5 was also greased. The application of the pressure due to the tightening of the hoodnut to the standard two hundred inch-pounds torque with a suitable wrench appeared to cause the rubber to actually flow into the groove 12 without causing the inner and outer periphery of the ring 11 to unduly extend. The grease allows any air in the groove 12 to readily escape as the hoodnut 10 is tightened.

One theory of the function of the groove in the hoodnut is that the pressure per unit area is increased around the inner and outer edges of the surface 15 so as to cause the seal 11 to tightly embed the roughness of the unglazed (and unfinished) portion of the insulator 5, and at the same time allowing the groove to receive and in fact draw into it a portion of the sealing ring 11 to which pressure is also applied by the hoodnut 10. In this connection, it is to be understood that the surface 15 along the upper edge of the insulator 5 is slightly rough and in the same condition as when it was rough ground. If this surface is finely finished or polished, then the sealing effect in FIG. 2 would be improved, but the ring 27 would still be deformed blocking the vent hole. However, the use of the groove 12 both improves the sealing effect and prevents undue deformity of the ring 11. It is also noted that the increased cross section of rubber at the groove 12 also tends to maintain resiliency over long periods of time.

Another theory of operation is that the groove collects the rubber and concentrates the pressures directly under it onto the surface 15 to cause any unevenness to more readily be embedded and form a tighter seal.

Regardless of the particular theory of the functioning of the groove, the practical results obtained are a highly satisfactory seal particularly useful for a pothead, although other uses may be found to which the seal may be put.

It is also to be understood that a pothead using this seal is constructed in the usual way by the insertion of hot insulating compound into the lower metal bell of the

pothead (not shown) with the vent screw 13 removed. As this compound rises in the metal bell and insulator section of the pothead, it ultimately begins to flow out of the vent 9, at which time the screw 13 with its O-ring gasket of neoprene rubber is placed is inserted into the vent 9 and the pothead gradually cooled. When the insulating compound has solidified, the source of the compound is removed and a closing plug is inserted into the connecting hole.

Having thus described one form of seal for a pothead 10 hoodnut as one specific embodiment of the present invention, it is desired to be understood that this form is selected to facilitate in the disclosure of the invention rather than to limit the number of forms which it may assume; and, it is to be further understood that various modifications, adaptations and alterations may be applied to the specific form shown to meet the requirements of practice without in any manner departing from the scope of the present invention.

What is claimed is:

20 In a pothead structure, an insulator body being hollow for allowing the sealed entrance of a cable at its lower end and having a flat circular surface at its upper end, a metal stem extending out of said insulator at its upper end and connected to said cable at its lower end, said 25 upper end of said stem being threaded and said lower end of said stem contacting said body of said insulator to prevent rotation of said stem relative thereto but providing the free passage of air and any fluid dielectric material inserted into said insulator body, a flat gasket 30 of resilient rubber material located on said flat circular surface at the upper end of said insulator body, and a capnut threaded onto said stem against said flat gasket, said capnut having a closable vent, and also having a 35 generally flat and now-confining circular surface matching the flat circular surface of said insulator body but having therein an annular groove centrally located radially in said flat surface relative to the flat surface of said insulator body, said annular groove having a cross-sectional area for receiving substantially all of the 40 resilient rubber material of the gasket displaced from its normal position by the tightening of the capnut onto said stem.
